FLUORESCENT LIGHT SOCKET
CONSTRUCTION

William L. Kelman, Providence, R. I.

Application December 28, 1946, Serial No. 719,045

2 Claims. (Cl. 200—51.07)

1

The present invention relates to fluorescent light fixtures, and has particular reference to a novel socket construction therefor.

The principal object of the invention is to provide an improved fluorescent light socket which has a movable bulb pin receiving member.

Another object of the invention is to mount a contact member in a fluorescent light socket which is rotatable to close the lighting circuit through the fluorescent light bulb.

Still another object of the invention is to provide a movable contact member which has contact receiving slots to freely admit the contact pins of a fluorescent light bulb without closing the circuit, and which is rotatable to lock the contact pins within the rotated contact member and close the circuit.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Fig. 1 is a perspective view of an illustrative fluorescent lighting fixture;

Fig. 2 is an inner view of one socket disclosing a contact member with slots for receiving the bulb pins;

Fig. 3 is a view similar to Fig. 2, the slots being shown in bulb pin contacting and locking position;

Fig. 4 is a view similar to Fig. 2, the contact member being removed;

Fig. 5 is an enlarged view of the rear of the contact member, in the position shown in Fig. 2, parts being broken away;

Fig. 6 is a similar view, in the position shown in Fig. 3;

Fig. 7 is a perspective view of one spring contact member;

Fig. 8 is a perspective view of the contact actuator for shifting the spring contact members to pin holding position; and

Fig. 9 is a perspective view of the contact member, the operating parts being removed to show the recessed structure thereof.

It has been found desirable to provide a novel socket for a fluorescent light fixture which has a movable part adapted to freely receive the pins of a fluorescent light bulb without closing the circuit, and movable to bring the pins into circuit closing position, the parts being so ar-

2

ranged that the pins are locked against removal when in circuit closing position. To this end, I provide a socket base which has fixed contact blades and has a rotatable contact member mounted therein; the contact member is provided with pin receiving slots, and has spring contacts which engage the contact blades and lock the bulb pins against removal when the contact member is turned.

Referring to the drawings, an illustrative fluorescent fixture 10 includes a light bulb 16 and two sockets 12 of similar construction which are mounted in spaced relation on a base 13, a transformer in the base having the usual 15 starter and wiring to complete the lighting circuit through a plug 14 and a standard switch 15. The invention resides in the construction of the socket element, Figs. 2 and 3 illustrating one socket, and Figs. 4 to 7 illustrating the operating parts thereof.

The socket 12 is of insulating material and includes a base portion 16 having the usual openings which receive holding screws, and an upright body member 17 which houses spaced 25 contact blades 18, 19, the upper portion of the body member being recessed to provide a chamber 20 into which the upper ends of the contact blades 18, 19 extend, as illustrated in Fig. 4. The upper rim 21 of the chamber 20 is provided with two spaced pin entrance openings 22, 23, and a cam element 24 of generally triangular shape is positioned off center in the chamber 20, see Fig. 4, and is shown in dotted lines in Figs. 5 and 6.

35 A movable contact member 25 of disk form and made of insulating material is rotatably mounted in the chamber 20, as by a pin support 26, and is provided with two spaced parallel slots 27, 28 which are in alignment with the entrance openings 22, 23 when the contact member 25 is in the position shown in Fig. 2, to receive the correspondingly spaced end pins of the bulb. In this position the pins enter the slots to substantially the center of the contact member 25, as indicated by the reference numerals 29, 30.

40 Two raised comma-like portions 31, 32 cooperate with the raised rim portion 23 of the contact member to provide recesses which receive two spring contacts 34, 35, which have bases 36 extending partially over the portions 31, 32, sides 37 which seat in slots 38, 39 provided in a raised portion 40, arcuate portions 41 which receive the tips of the bulb pins, and 45 spring arms 42 which bend inwardly and which

are initially adjacent to but spaced from the bulb pin ends, and are movable to resiliently engage the bulb pins and lock them against the arcuate portions 41.

A shaped actuator 43 of insulating material, see Fig. 9, has a body portion 44 and two parallel legs 45, 46, the body portion 44 being positioned between the spring arms 42 and the legs 45, 46 being movably seated in slots 47, 48 in the raised rim portion 33, whereby radial outward movement of the actuator presses the curved portions of the spring arms to bring their ends into resilient contact with the bulb pins.

The radial outward movement of the actuator 43 is effected by the fixed cam element 24 when the contact member is rotated on its pin support 26, the contact member assuming the position shown in Fig. 6. In this position the bases 36 of the spring contacts engage the upper ends of the contact blades 18, 19, and the bases 36 are preferably provided with projections 49 which seat into depressions 50 in the ends of the contact blades for obtaining good retaining engagement.

When the bulb 11 is to be inserted into the sockets, the contact members are in the position of Fig. 2, whereupon the bulb pins are readily inserted into the slots 27, 28 through the openings 22, 23 until they engage the arcuate seats 41. In this position the bases 36 of the spring contacts do not engage the contact blades 18, 19, and the cam element 24 does not engage the actuator; the tension of the spring arms has therefore moved the actuator inwardly so that the ends of the spring arms have moved inwardly and do not interfere with insertion of the bulb pins.

The bulb 11 is now turned, whereupon the contact members assume the position shown in Fig. 6. The bases 36 now engage the contact blades 18, 19, the cam element 24 has moved the actuator 43, and the spring arms 42 are tightly pressed against the bulb pins to lock the pins against the arcuate portions 41. Further, the slots 27, 28 are now in the position shown in Fig. 3, whereby the ends of the slots 27, 28 are closed.

The tension of the projections 49 in the depressions 50 on the contact blade ends is normally sufficient to lock the parts together against inadvertent turning, but, if desired, a spring snap of standard type such as a cylinder with spring pressed ball may be set in a recess in the raised portion 40 to cooperate with a slight depression in the lower portion 21 of the socket to obtain further resistance to inadvertent turning.

While I have described a specific embodiment of the invention, it is obvious that the spring contacts may be locked in the contact members by molding them in, that the parts may be arranged so that the bulb end pins when positioned in the contact member may themselves be utilized as contact elements which cooperate with fixed contact blades or the like in the socket box, and that changes in the size, shape, position and material

of the parts may be made to suit different requirements for different fluorescent light socket constructions, without departing from the spirit and the scope of the invention as defined in the appended claims.

I claim:

1. A socket construction for a fluorescent light fixture, comprising a base having a circular recess, spaced contact blades mounted in said base and extending into said recess, a pin end receiving member rotatably mounted in said recess and having spaced slots for receiving the pin ends of a fluorescent bulb, a contact element in each slot of said receiving member engageable by the received pin end, said contact elements being adapted to engage said spaced contact blades in one position of the pin end receiving member, and means for locking the pin ends in engagement with the contact elements, said means including spring arms on said contact members movable to engage the pin ends when the pin end receiving member is rotated to engage the contact elements with the spaced contact blades.

2. A socket construction for a fluorescent light fixture, comprising a base having a circular recess, spaced contact blades mounted in said base and extending into said recess, a pin end receiving member rotatably mounted in said recess and having spaced slots for receiving the pin ends of a fluorescent bulb, contact elements mounted in said receiving member and engageable by the received pin ends, said contact elements being adapted to engage said spaced contact blades in one position of the pin end receiving member, and means for locking the pin ends in the slots, said means including spring arms on said contact members, an actuator movably mounted in said pin end receiving member and adapted to press on said spring arms and move them into contacting locking engagement with the pin ends, and a fixed cam on said base for moving said actuator when the pin end receiving member is rotated to engage the contact elements with the spaced contact blades.
